CLAIM

The ornamental design for a charging device for an electric vehicle, as shown and described.

DESCRIPTION

FIG. 1 is a front, top perspective view of a charging device for an electric vehicle, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged view of the enclosed portion of the charging device for an electric vehicle labeled "9" in FIG. 1; FIG. 10 is an enlarged view of the enclosed portion of the charging device for an electric vehicle labeled "10" in FIG. 1; and,

FIG. 11 is an enlarged view of the enclosed portion of the charging device for an electric vehicle labeled "11" in FIG. 2.

The dashed lines in the figures illustrate portions of the charging device for an electric vehicle that form no part of the claimed design. The dash dot dash lines in FIGS. 1, 2, 9, 10 and 11 are for the purpose of illustrating the enlarged view indicators and form no part of the claimed design.
